DRIER

Edwin F. Daley, Brooklyn, N. Y., assignor to Frederick S. Stout, Camden, N. J.

Application August 3, 1940, Serial No. 350,495

8 Claims.

(Cl. 34—44)

This invention relates to drying mechanisms and, more particularly, to an apparatus for drying materials such as hides or similar materials which have been pretreated with moist conditioning substances and which must, in order to be properly worked, be dried to an approximately accurate moisture content.

An important object of the invention is to provide an apparatus for this purpose which, within reasonable limits, will not be subject to changes in atmospheric conditions such as changes in humidity or temperature.

Another object of the invention is to provide an apparatus of this character which may be very readily regulated and in which adjustments are provided enabling compensation for seasonal changes.

Another object of the invention is to provide an apparatus of this character which is particularly adapted for use in drying hides, and in which the desired dehydration is obtained without excessive shrinkage.

These and other objects I attain by the construction shown in the accompanying drawing wherein, for the purpose of illustration, I have shown a preferred embodiment of my invention and wherein:

Fig. 1 is a semi-diagrammatic sectional view through a drying apparatus constructed in accordance with my invention; and

Fig. 2 is a detail elevational view of the adjusting mechanism.

Referring now more particularly to the drawing, the numeral 10 generally designates an elongated chamber through which passes a reticulate conveyer 11, direction of movement of the conveyer being indicated by the arrow A. Adjacent the discharge end of the chamber 10 is arranged an inlet 12 receiving the discharge from a blower 13 which is passed over a suitable heating coil 14. Such coil may, for example, be a steam coil, and has associated therewith a regulating valve 15 which is controlled through a thermostat 16 disposed within the chamber and adjacent the upper surface of the conveyer at the discharge end thereof. As diagrammatically illustrated, this thermostat is of that type controlling delivery of a supply of operating air from a source 17 to the control valve 15 for regulating the supply of steam or other heating fluid to the coil 14.

At the opposite end of chamber 10 is an outlet 18, this outlet being equipped with an exhaust blower 19. It will be obvious that were the chamber 10 simply provided with heated air introduced by the blower 13 and exhausted by blower 19, there

would be a decided stratification within the chamber and, in accordance with my invention, this stratification is advantageously employed to insure proper drying of the articles moving through the chamber upon the conveyer 11. This I accomplish by arranging within the chamber, between the inlet and outlet thereof, a baffle, or baffles, which are adjustably regulated by the humidity of the hides or other materials conveyed. As at present shown, two such baffles are illustrated; one of the baffles, indicated at 20, being located between the inlet and outlet and the second baffle 21 being located adjacent the outlet 18 and coacting with a fixed baffle 18a depending from the inner edge of outlet 18. A humidostat 22 is arranged adjacent the upper surface of the conveyer at a point beyond the baffle 20 and, preferably, where two baffles are employed as shown, between these baffles. Baffles 20 and 21 are pivoted so that they may be adjustably regulated, and the regulation thereof is preferably automatically effected by humidostat 22. As at present shown, humidostat 22 controls the circuit of a reversible motor 23 by means of which an arm 24 is rotated. This arm has adjustably mounted thereon, as at 25, a connection through which flexible elements 26, 27 may be operatively connected to arms 28 attached to the respective baffles 20 and 21. The connection of flexible elements 26, 27 to the arms 28 is preferably, likewise, made adjustable, as indicated at 29.

It will be obvious that by shifting baffles 20 and/or 21 the highly heated air which would ordinarily rise to the top in chamber 10 is forced downwardly and thus caused to pass directly over the surface of the hides and through the reticulate conveyer to engage against both the upper and lower surfaces thereof at a greatly increased speed. If the humidity content of the air after the heat treatment is sufficiently high, the humidostat will actuate motor 23, causing the baffle, or baffles, to move downwardly and increase the speed and temperature of air moving across the surface of the hides, and vice versa. Variations in the temperature of the air or of the humidity thereof will, likewise, be taken care of by thermostat 16 and humidostat 22 and, accordingly, a very uniform product may be obtained. In event the changes necessary are excessive as, for example, due to changes in season, as between summer and winter, further adjustment to insure proper conditioning of the material may be obtained both at the control arm 24 and in the arms 28 connected to baf-

files 20 and 21. It will be obvious that the temperature of the air adjacent the inlet 12 will be affected by the moisture content of the hides approaching this inlet end and with a reduction of temperature thermostat 16 will act to increase the temperature of the incoming air. By reason of these controls, a very accurate control of the moisture content of the articles under treatment may be obtained.

Since the construction illustrated is, obviously, capable of considerable modification without in any manner departing from the spirit of the invention, I do not wish to be understood as limiting myself thereto except as hereinafter claimed.

I claim:

1. In a drier, an elongated casing, an endless support having a run moving through the casing from end to end thereof, an inlet for the casing adjacent that end thereof at which said run leaves the casing, an outlet for the casing at the opposite end thereof, an adjustable baffle arranged between said inlet and outlet and adapted to deflect air passing from the inlet to the outlet downwardly upon material arranged on said run to an extent controlled by the position of said baffle, means including a humidostat arranged in the casing for positioning said baffle, heating means for air introduced through said inlet and a thermostat arranged between said baffle and the inlet and adjacent the upper surface of said run for controlling the temperature of the incoming air.

2. In a drier, an elongated casing, an endless support having a run moving through the casing from end to end thereof, an inlet for the casing adjacent that end thereof at which said run leaves the casing, an outlet for the casing at the opposite end thereof, an adjustable baffle arranged between said inlet and outlet and adapted to deflect air passing from the inlet to the outlet downwardly upon material arranged on said run to an extent controlled by the position of said baffle, heating means for air introduced through said inlet, a thermostat arranged between said baffle and the inlet and adjacent the upper surface of said run for controlling the temperature of the incoming air, and a humidostat arranged between said baffle and the outlet and controlling the position of said baffle.

3. In a drier, an elongated casing, an endless support having a run moving through the casing from end to end thereof, an inlet for the casing adjacent that end thereof at which said run leaves the casing, an outlet for the casing at the opposite end thereof, an adjustable baffle arranged between said inlet and outlet and adapted to deflect air passing from the inlet to the outlet downwardly upon material arranged on said run to an extent controlled by the position of said baffle, means including a humidostat arranged in the casing for positioning said baffle and controllable heating means for heating the air introduced through said inlet.

4. In a drier, an elongated casing, an endless support having a run moving through the casing from end to end thereof, an inlet for the casing adjacent that end thereof at which said run leaves the casing, an outlet for the casing at the opposite end thereof, an adjustable baffle arranged between said inlet and outlet and adapted to deflect air passing from the inlet to the outlet downwardly upon material arranged on said run to an extent controlled by the position of said baffle, controllable heating means for heating the

air introduced through said inlet, and a humidostat arranged between said baffle and the outlet and controlling the position of said baffle.

5. In a drier, an elongated casing, an endless support having a run moving through the bottom of the casing from end to end thereof, an inlet for the casing adjacent that end thereof at which said run leaves the casing, an outlet for the casing at the opposite end thereof, an adjustable baffle arranged upon a transverse pivot adjacent the top of the casing and between said inlet and outlet and adapted to deflect air passing from the inlet to the outlet downwardly upon material arranged on said run to an extent controlled by the position of said baffle, means including a humidostat arranged in the casing for positioning said baffle, heating means for air introduced through said inlet and a thermostat arranged between said baffle and the inlet and adjacent the upper surface of said run for controlling the temperature of the incoming air.

6. In a drier, an elongated casing, an endless support having a run moving through the bottom of the casing from end to end thereof, an inlet for the casing adjacent that end thereof at which said run leaves the casing, an outlet for the casing at the opposite end thereof, an adjustable baffle arranged upon a transverse pivot adjacent the top of the casing and between said inlet and outlet and adapted to deflect air passing from the inlet to the outlet downwardly upon material arranged on said run to an extent controlled by the position of said baffle, heating means for air introduced through said inlet, a thermostat arranged between said baffle and the inlet and adjacent the upper surface of said run for controlling the temperature of the incoming air, and a humidostat arranged adjacent said run between said baffle and the outlet and controlling the position of said baffle.

7. In a drier, an elongated casing, an endless support having a run moving through the casing from end to end thereof, an inlet for the casing adjacent that end thereof at which said run leaves the casing, an outlet for the casing at the opposite end thereof, an adjustable baffle arranged between said inlet and outlet and adapted to deflect air passing from the inlet to the outlet downwardly upon material arranged on said run to an extent controlled by the position of said baffle, controllable heating means for heating the air introduced through said inlet, means to adjust said baffle including a reversible motor and a humidostat arranged between the baffle and said outlet and controlling the position of the baffle.

8. In a drier, an elongated casing, an endless support having a run moving through the casing from end to end thereof, an inlet for the casing adjacent that end thereof at which said run leaves the casing, an outlet for the casing at the opposite end thereof, an adjustable baffle arranged between said inlet and outlet and adapted to deflect air passing from the inlet to the outlet downwardly upon material arranged on said run to an extent controlled by the position of said baffle, controllable heating means for heating the air introduced through said inlet, a shaft upon which said baffle is mounted, a second shaft, means for reversely rotating said second shaft, a humidostat arranged between said baffle and said outlet and controlling the position of said second shaft and an adjustable connection between the first and second shafts.
